COMBINED SLIDE PROJECTOR AND SLIDE TRAY

David E. Hansen, Fairport, N.Y., assignor to Eastman Kodak Company, Rochester, N.Y., a corporation of New Jersey

Filed Dec. 22, 1961, Ser. No. 68,025

Term of patent 14 years

(Cl. D61—1)

The single figure is a front perspective view of a combined slide projector and slide tray showing my new design.

The side and rear, not shown, have the same plain appearance as the side shown, and the bottom is conventional.

I claim:

The ornamental design for a combined slide projector and slide tray, as shown and described.
